UNITED STATES PATENT OFFICE.

CHARLES C. STAPEL, OF AVALON, PENNSYLVANIA, ASSIGNOR OF ONE-HALF TO JESSE L. COLEMAN, OF PITTSBURGH, PENNSYLVANIA.

SANITARY FOUNTAIN.

1,184,042.

Specification of Letters Patent. Patented May 23, 1916.

Application filed April 4, 1913. Serial No. 758,917.

To all whom it may concern:

Be it known that I, CHARLES C. STAPEL, a citizen of the United States, and resident of Avalon, in the county of Allegheny and State of Pennsylvania, have invented a new and useful Improvement in Sanitary Fountains; and I do hereby declare the following to be a full, clear, and exact description thereof.

10 My invention relates to a sanitary drinking fountain and the object thereof is to provide a device of this character in which the nozzle or mouth piece when not in use will stand in a depending or inverted position, so that the surface and orifice thereof will not collect dust or dirt, as is the case with fountains of this character in which the mouth piece normally stands in upright or upwardly extending position.

15 20 A further object is to provide means whereby the turning on of the water simultaneously turns the mouth piece into upright or drinking position.

25 A further object is to provide means whereby when the handle of the cock is released the nozzle or mouth piece will be automatically returned to inverted position.

30 Other objects and advantages of the invention will appear from the following description of a preferred embodiment of the invention, which is illustrated in the accompanying drawings, in which—

35 Figure 1 is a plan view of the fountain, parts being in section for clear illustration; Fig. 2 is a sectional view on the line 2—2 Fig. 1; Fig. 3 is a sectional view of a detail on line 3—3 Fig. 1 and Fig. 4 is an end view of the leader and the nozzle or mouth piece looking from the left Fig. 1.

40 In the embodiment of my invention herein selected for illustration, 1 indicates the catch basin of the fountain having the drain opening 2 preferably protected by a strainer 3. In this preferred form, a back or wall plate 4 is provided within which the standard 5 of the fountain proper is mounted. This standard includes the base or wall plate 6, the column or standard 7 having branching arms 8 and 9. The standard 7 is provided with the water passage 10 which is extended at 11 through the hollow arm 9 of the bracket. The outer ends of the bracket arms 8 and 9 form bearings for the hollow stem or leader 12 which conducts the water

55 to the nozzle or mouth piece 13. This leader 12 has a reduced stem 13 to which a handle 14 may be secured. At the right end, as viewed in Fig. 1 the leader is provided with a stop shoulder 14 against which a spring 15 within the bearing cavity 16 of the 60 bracket arm 8 is housed, a nut 17 confining the spring within said cavity. On the end of the leader opposite the shoulder 14 is a cam face 18 adapted to be engaged by a corresponding cam face 19 of a nut 20 screwed 65 into the outer end of the bearing cavity 16. The opposite bracket arm 9 is provided with a valve seat 21 just within which is a bearing piece or spider 22 forming a support for the valve stem 23 of the valve 24. Projecting from the opposite side of the valve is a second stem 25 which is supported by a cross piece or strut 26 of a nut 27 secured into the bearing member of the hollow 70 bracket arm 9. The end of the leader 12 75 adjacent the valve is provided with a cross piece 28 as shown in Fig. 4 which forms a bearing for the valve stem 23 and a spring 29 is interposed between the outer face of the valve and the nut 27. In Fig. 3 it will 80 be seen that the spaces 30 on either side of the valve stem supporting piece 22 will allow passage of the water to the leader 12 and the spaces 31 on either side of the cross piece 28 of the leader will permit entrance of the 85 water to the leader and to the nozzle or mouth piece 13.

Upon turning the leader 12 by means of the handle 14 the cam faces 18 and 19 respectively will cause the leader to move to 90 the left as viewed in Fig. 1, thus unseating the valve from its valve seat 21 and simultaneously turning the nozzle or mouth piece up to upright or drinking position, said mouth piece being normally and preferably 95 in a pendant position at an angle of about 45° as indicated in Figs. 1 and 2. The pressure of the spring 15, aided by the pressure of the water against the opposite end of the leader 12 and the pressure of the spring 100 29 will serve to move the leader to the right as shown in Fig. 1 and the cam faces 18 and 19 will cause the leader to turn in the reverse direction, thus permitting the valve 24 to close under pressure of its spring 29 and 105 under pressure of the water and returning the nozzle or mouth piece to depending position.

It is sometimes desirable to provide means to prevent users of the fountain from spraying water from the nozzle laterally by partially closing the water vent 13^a in the nozzle with the finger, said nozzle therefore is provided with a lateral outlet 32 extending back toward base and the face of the nozzle at the face provided with a groove 33, thus permitting the water to escape through this port 32 when the vent is partially closed and by means of the groove 33 preventing any possibility of the complete closing of the outlet by the finger of the user. Therefore should the vent be partially closed the pressure of the water would be relieved by this lateral port.

While I have herein described particular embodiments of my invention, it is to be understood that the same may be altered in details and arrangements of parts within the scope of the appended claims.

What I claim is:

1. In a sanitary drinking fountain, the combination with a water supply, of a fountain mechanism connected therewith, comprising a hollow valve stem, bearing arms supporting said stem at either end, one of said arms forming a connection with the water supply, a nozzle normally extending downward from said stem between said bearing arms, a valve in said supply arm, a handle at one end of said stem, a means whereby when said stem is turned to bring said nozzle to upright position, the valve

will be opened to connect the supply arm 35 with said nozzle.

2. In a sanitary drinking fountain, a combination with a water supply, of a fountain mechanism connected therewith, comprising a forked supporting member, having one portion thereof hollow to form a connection with the water supply, a valve stem having one end supported by said supply portion, a valve in said supply portion, and means on said stem to operate the same, said stem having a nozzle projecting downward therefrom between the branches of said supporting member and means to turn said nozzle to upright position and simultaneously to connect said nozzle with the water supply.

3. In a sanitary drinking fountain, the combination with a water supply, a fountain mechanism connected therewith, comprising a pair of supporting arms, a valve stem supported at either end within said arms respectively, a nozzle connected with said stem intermediate of said arms, and means constructed and arranged to connect said nozzle with the water supply, and to turn the nozzle to upright operative position upon rotating said stem.

In testimony whereof, I the said CHARLES C. STAPEL have hereunto set my hand.

CHARLES C. STAPEL.
